CLUSTER BREAKER FOR CHERRIES

Alvin J. Gotelli and Melvin W. Oneto, Stockton, Calif., assignors to Oneto-Gotelli Co., Stockton, Calif., a co-partnership

Application December 10, 1956, Serial No. 627,270

17 Claims. (Cl. 146—1)

This invention relates in general to apparatus for use in the fresh cherry packing industry.

Fresh cherries, as picked, are frequently in compound or cluster form; i. e., two or more individual fruits whose stems are connected together at the opposite end. Before such cherries are packed in a box for shipment to the market it is necessary that they be singularly separated, but with the stems remaining attached to the fruit. This is accomplished by splitting or cutting the stems apart at or near the point of connection.

Apparatus for this purpose is known as a "cluster breaker"; the present invention being particularly directed to, and a major object being to provide, an improved power driven apparatus of such type.

Another important object of the invention is to provide a cluster breaker which includes—in each of a multiplicity of units embodied in the apparatus—a driven rotary saw and novel mechanism operative to pick up the stems of cherry clusters moving on, and advancing with, a conveyor and to orient and guide such stems so that the saw cuts them apart at or near the point of connection.

An additional object of the invention is to provide a cluster breaker, as in the preceding paragraph, wherein each such unit comprises—in novel combination with the rotary saw—a pick-up finger adapted to receive and so orient and guide the cherry clusters as they move toward the saw; the fruit remaining on the adjacent conveyor, the stems straddling said finger, and the point of connection remaining above the finger for severance by the saw.

Still another object of the invention is to provide a cluster breaker wherein each such unit includes additionally a novel deflector disposed ahead of the saw and above the pick-up finger; such deflector functioning not only to assure of straddling of each picked-up cluster over the finger, but also prevents the fruit from riding into—and being undesirably cut by—said saw.

A further object of the invention is to provide a cluster breaker which is constructed so that it may be used in conjunction with a conventional or existing type of endless belt sorting conveyor.

It is also an object of the invention to provide a cluster breaker which is designed for ready and economical manufacture and long service with a minimum of maintenance or repair being required.

A still further object of the invention is to provide a practical, reliable, and durable cluster breaker, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation, longitudinally foreshortened, of the cluster breaker.

Fig. 2 is a top plan of the same, foreshortened both longitudinally and transversely.

2

Fig. 3 is an enlarged fragmentary longitudinal elevation, partly in section, showing one of the cluster breaking units, of which the apparatus includes a multiplicity.

Fig. 4 is an enlarged fragmentary elevation, mainly in section, showing the manner of mounting of one of the saws on the related cross shaft, and the extent of dependency of the lower portion of the saw into the adjacent slotted pick-up finger.

Fig. 5 is an enlarged fragmentary view showing, in front elevation, one of the pick-up finger supporting clamps; the finger being in section.

Referring now more particularly to the drawings and to the characters of reference marked thereon, the cluster breaker as here shown is especially adapted for use in connection with an endless belt sorting conveyor, indicated generally at 1, and which includes transversely spaced side beams 2 between which there extends the upper run 3 of a driven endless sorting belt. Said upper run 3 of the endless sorting belt travels in the direction indicated by the arrow in Fig. 1, and in operation supports and advances picked fresh cherries, many of which are in clusters.

The present invention provides a cluster breaker, for cooperation with the conveyor 1, which comprises an open rectangular frame 4 having longitudinal side beams 5 and transverse end beams 6 secured together in rigid relation. The frame 4 is disposed lengthwise and in overlying relation to the conveyor 1, with the longitudinal side beams 5—which are of angle iron—seating on the side beams of said conveyor 1. With this arrangement the frame 4—which supports all of the mechanism of the cluster breaker—is effectively yet simply mounted in connection with the conveyor 1, and for cooperation of the cluster breaker therewith.

At longitudinally spaced points the cluster breaker frame 4 carries full-width cross shafts 7 whose end portions are provided with journals 8 vertically adjustably mounted on corresponding posts 9 upstanding from the longitudinal side beams 5; vertical adjustment of each journal 8 being accomplished by means including opposed screws 10.

Adjacent but ahead (relative to the direction of travel of the upper run 3) of each cross shaft 7 and parallel thereto, there is a cross rod 11 fitted at the ends with slide blocks 12 vertically adjustably mounted in fixed guides 13 which upstand from the longitudinal side beams 5; the blocks 12 being vertically adjustable by opposed screws 14.

A cross bar 15 is disposed slightly to the rear, and some distance above, each cross shaft 7; such cross bar being fitted at each end with a slotted bracket 16 vertically adjustably bolted, as at 17, to the face of the adjacent post 9.

Each cross shaft 7 carries a row of transversely spaced rotary or circular saws 18 whose equi-distant spacing is maintained by spacer sleeves 19; the assembly of said rotary saws 18 and spacer sleeves 19 being axially clamped, on the related cross shaft 7, between a fixed collar 20 at one end and a locking nut 21 at the other end; such nut being threaded on said cross shaft.

The rotary saws 18 on each cross shaft 7 are in transversely staggered relation to the corresponding saws on the adjacent cross shafts, whereby to run in different vertical longitudinal planes.

All of the cross shafts 7, and the rotary saws 18 thereon, are simultaneously driven in the direction indicated by the arrow in Fig. 3; this being accomplished by an endless belt and pulley assembly, indicated generally at 22, which extends between said cross shafts 7 at one end thereof and an electric motor 23 mounted on a platform 24 secured to one corner of the frame 4.

The individual rotary saws 18 comprise one of the

elements of a cluster breaking unit, each indicated generally at 25, of which the apparatus includes a multiplicity; the number of said cluster breaking units 25—carried by each transverse assembly of a cross shaft 7, cross rod 11, and cross bar 15—equaling the number of saws on said cross shaft.

As each cluster breaking unit is an exact counterpart of all of the others, a description of one will suffice for all.

Each cluster breaking unit 25 comprises, in association with the related rotary saw 18, a longitudinally extending pick-up finger 26 secured at one end to the corresponding cross rod 11 by means of a rotatably adjustable clamp 27; the clamp depending from the cross rod 11 and at the bottom securing the adjacent end of the pick-up finger 26 in longitudinally adjustable relation, all as shown particularly in Fig. 5.

From the clamp 27 the pick-up finger 26 extends at a rearward and downward incline and terminates at its free or rearward end substantially at or in light touching engagement with the surface of the upper run 3 of the driven endless sorting belt. The rearward or free end portion of the pick-up finger 26 is tapered, as shown.

Intermediate its ends the pick-up finger 26 is formed with a longitudinal slot 28 in which the lower portion of the related rotary saw 18 runs; this relationship of the parts being accomplished by appropriate adjustment of the cross shaft 7, cross rod 11, and the clamp 27.

The cross bar 15 has affixed thereto, and directly to the rear of the rotary saw 18, a depending saw guard and fruit deflector 29; said deflector extending downwardly to a lower end termination closely adjacent but spaced from the corresponding pick-up finger 26. The saw guard and fruit deflector 29 is alined with the corresponding pick-up finger 26 in a longitudinal vertical plane, and on the back side—i. e. facing contra to the direction of travel of the upper run 3 of the endless sorting belt—said deflector is V-shaped in plan, whereby to provide forwardly diverging deflecting surfaces.

Additionally, the deflector 29 is rounded rearwardly and upwardly at the lower end, as at 30.

In use of the above described cluster breaker each of the multiplicity of cluster breaking units 25 functions in the following manner, and as shown in Fig. 3.

The upper run 3 of the driven endless sorting belt is fed the picked fresh cherries, which are spread out rather loosely on the belt so that no pile-up exists; many of the cherries being in clusters, as indicated—for example—generally at 31.

Each such cluster 31 includes at least two stems 32 extending from the corresponding fruit 33 to a point of connection 34. As the upper run 3 moves forwardly, the cherry clusters 31 are correspondingly advanced. Because of the multiplicity of cluster breaking units 25 and their relative transversely staggered relation, each cherry cluster 31 will—as it advances—be picked up by, and straddled upon, the pick-up finger 26 of one of the cluster breaking units 25.

When this occurs the stems 32 depend on opposite sides of the engaged pick-up finger 26, with the point of connection 34 of the stems above and generally riding the finger; the fruit 33 remaining on the upper run 3 and continuing to advance therewith. As the fruit 33 so advances, the finger straddling cluster 31 is likewise drawn forward until the point of connection 34 reaches—and is severed by—the rotary saw 18, whose lower portion runs in the longitudinal slot 28 to assure that the cutting operation is wholly effective.

With such operation the fruit 33—with the now cut-apart stems 32a remaining thereon—continues to advance with said upper run 3, being subsequently removed from the conveyor 1 beyond the cluster breaker.

The saw guard and fruit deflector 29, disposed above each pickup finger 26, not only serves the purpose of a guard, but also assures that the fruit 33 of any finger

5 picked-up cherry cluster 31 will be deflected laterally away from the plane of the adjacent saw 18 and onto the upper run 3 in order that the cluster may be properly advanced and severed by said saw at the point of connection 34.

From the foregoing description it will be readily seen that there has been produced such an apparatus as will substantially fulfill the objects of the invention, as set forth herein.

While this specification sets forth in detail the present and preferred construction of the apparatus, still in practice such deviations therefrom may be resorted to as do not form a departure from the spirit of the invention, as defined by the appended claims.

Having thus described the invention, the following is claimed as new and useful, and upon which Letters Patent are desired:

1. A cherry cluster breaking unit comprising, in association with a driven conveyor belt adapted to receive and advance said clusters, a support adjacent the belt, a longitudinal cluster pick-up finger disposed above the belt, means mounting the finger in connection with the support, the finger extending free rearwardly from the mounting means, and a cluster separating cutter cooperating with the finger intermediate its ends.

2. A cherry cluster breaking unit, as in claim 1, in which the finger inclines downwardly to its rear end, and such end being closely adjacent the belt.

3. A cherry cluster breaking unit, as in claim 2 in which an adjacent portion of the finger is tapered toward said rear end.

4. A cherry cluster breaking unit comprising, in association with a driven conveyor belt adapted to receive and advance said clusters, a support adjacent the belt, a longitudinal cluster pick-up finger disposed above the belt, means mounting the finger in connection with the support, the finger extending free rearwardly from the mounting means, a cluster separating cutter cooperating with the finger intermediate its ends, a fruit deflector disposed rearwardly of the cutter but ahead of the rear end of the finger, and means mounting the deflector in connection with the support.

5. A cherry cluster breaking unit, as in claim 4, in which said finger, cutter, and deflector are alined longitudinally of the direction of travel of the belt; the deflector terminating at its lower end adjacent but clear of the finger.

6. A cherry cluster breaking unit, as in claim 4, in which the deflector terminates at its lower end adjacent and in vertical alinement with the finger but clear thereof; said deflector being V-shaped in plan and disposed to provide forwardly diverging working faces.

7. A cherry cluster breaking unit comprising, in association with a driven conveyor belt adapted to receive and advance said clusters, a support adjacent the belt, a longitudinal cluster pick-up finger disposed above the belt, means mounting the finger in connection with the support, the finger extending free rearwardly from the mounting means, and a driven rotary cutter cooperating with the finger intermediate its ends and from above.

8. A cherry cluster breaking unit, as in claim 7, in which the rotary cutter has its axis disposed transversely of the finger; the latter having a longitudinal slot therein from the top, and the lower portion of the rotary cutter running in said slot.

9. A cherry cluster breaking unit comprising, in association with a driven conveyor belt adapted to receive and advance said clusters, a support adjacent the belt, a longitudinal cluster pick-up finger disposed above the belt, means mounting the finger in connection with the support, the finger extending free rearwardly from the mounting means, a driven transverse shaft above the finger, means journaling the shaft on the support, and a rotary saw on the shaft in vertical alinement and cooperating with the finger intermediate its ends.

10. A cherry cluster breaking unit comprising, in association with a driven conveyor belt adapted to receive and advance said clusters, a support adjacent the belt, a longitudinal cluster pick-up finger disposed above the belt, means mounting the finger in connection with the support, the finger extending free rearwardly from the mounting means, a driven transverse shaft above the finger, means journaling the shaft on the support, a rotary saw on the shaft in vertical alinement and cooperating with the finger intermediate its ends, a saw guard and fruit deflector disposed in longitudinal alinement and rearwardly of the saw but ahead of the rear end of the finger, and means mounting the saw guard and fruit deflector in connection with the support.

11. A cherry cluster breaking unit, as in claim 10, in which said guard and deflector is vertically elongated and rearwardly V'd; the lower end thereof terminating adjacent but clear of the finger, and said end being rearwardly and upwardly rounded.

12. A cherry cluster breaking unit comprising, in association with a driven conveyor belt adapted to receive and advance said clusters, a frame adjacent the belt, a driven transverse shaft extending above the belt and journaled on the frame, a cross rod extending above the belt and secured to the frame, the cross rod being adjacent but ahead of the transverse shaft, a longitudinal cluster pick-up finger disposed above the belt, means attaching the finger at its forward end to the cross rod, the finger thence extending at a rearward and downward incline below the cross shaft and to a free end termination rearwardly thereof and close to the belt, and a rotary saw on the shaft cooperating with the finger.

13. A cherry cluster breaking unit, as in claim 12, in which the finger is longitudinally slotted from the top, and the lower portion of the saw running in the slot.

14. A cherry cluster breaking unit comprising, in association with a driven conveyor belt adapted to receive and advance said clusters, a frame adjacent the belt, a driven transverse shaft extending above the belt and journaled on the frame, a cross rod extending above the belt and secured to the frame, the cross rod being adjacent but ahead of the transverse shaft, a longitudinal cluster pick-up finger disposed above the belt, means attaching the finger at its forward end to the cross rod, the finger thence extending at a rearward and downward incline below the cross shaft and to a free end termina-

tion rearwardly thereof and close to the belt, a rotary saw on the shaft cooperating with the finger, a cross bar extending above the belt and secured to the frame, said cross bar being disposed rearwardly of the transverse shaft and above the finger, and a saw guard and fruit deflector fixed on the cross bar and depending in alinement rearward of the saw and to a lower end termination adjacent but clear of said finger.

15. A cherry cluster breaker comprising, in association with a driven conveyor belt adapted to receive and advance said clusters, a plurality of longitudinally spaced transverse rows of cluster breaking units supported above and cooperating with the belt, the corresponding units of adjacent rows being in staggered relation; each such unit including a longitudinal cluster pick-up finger inclined downwardly and rearwardly to a free end termination close to the belt, and a cluster separating cutter cooperating with the finger ahead of said free end.

16. In a machine to break cherry clusters each of which comprises at least two cherries and stems projecting therefrom and connected together at their outer end, a cluster breaking unit comprising, in association with a driven conveyor belt adapted to receive and advance said clusters, an elongated cluster pick-up finger disposed above and extending lengthwise of the belt with a downward slope rearwardly relative to the direction of movement of the belt to a termination adjacent the belt whereby to straddle a cluster advancing with the belt and thus raise the point of connection of the stems above the finger, and a transverse-axis rotary cutter transversely alined with and above the finger intermediate its ends, said finger having a slot into which the cutter projects without depending below the finger.

17. A cluster breaking unit, as in claim 16, in which the vertical distance from the rear edge of the cutter adjacent the finger to the belt is less than the length of any stem.
